242,110

PARTICLE SEPARATOR FOR A VACUUM CLEANER

Bjorn Snapa, Enebakkv. 230 B, Oslo 11, Norway
Filed May 27, 1975, Ser. No. 581,120

Claims priority, application Norway Nov. 25, 1974

Term of patent 14 years

Int. Cl. D15—05

U.S. Cl. D15—62

FIG. 1 is a side elevational view of a particle separator for a vacuum cleaner showing my new design;

FIG. 2 is a top plan view thereof; and

FIG. 3 is a bottom perspective view thereof.

I claim:

The ornamental design for a particle separator for a vacuum cleaner, as shown and described.
